APPARATUS FOR TREATING HYDROCARBON VAPORS

Application filed May 7, 1929. Serial No. 361,015.

Our invention relates to the treatment of hydrocarbon oils and especially to such treatment for the purpose of producing motor fuel from petroleum by the process commonly known as cracking. The present application is a continuation in part of our prior copending application filed February 16, 1928, Serial No. 254,753, in which we have described and claimed an improved method of cracking under vacuum and a complete plant for practicing the same. In the present case we shall describe the same general system, together with improved primary and cracking stills combined in one structural unit, and shall claim said unit construction, as well as certain specific features and methods of operation of the plant as a whole.

Very briefly stated, the invention we present has for its basis the discovery on our part that by cracking, fractionating, and cooling under a vacuum, in whole or in part, we can increase the yield of a product containing unsaturated compounds and aromatics which is eminently suitable for motor fuel; and that by suitably regulating the temperatures and pressures (sub-atmospheric) in different parts of the system, we can not only greatly economize heat and thereby economize fuel, but we can also produce a product containing practically 100% of the desired unsaturates and aromatic compounds.

Our apparatus, as it will be described, comprises a preheating still for the charging stock, a cracking still, preferably preceded by a flashpot into which the oil from the preheater is expanded into vapors, and a succession of interrelated fractionating towers or dephlegmators with one or more vacuum pumps, heat exchanger, and cooler and separator, an absorption tower, all arranged as will be described in detail hereinafter. In addition to the regulation of pressures in each element of the system, from the preheater to the separator and absorber, we have found it possible to arrange a graduated heat transfer by means of which make-up oil, or refluxed fractions to be cracked, take up practically all the heat

energy in the cracked vapors, in a counter current progression through the fractionators. The make-up oil and refluxed fractions instead of going direct to the cracking still, have their temperature raised so that they can be converted into vapors in the flashpot, from which the vapors pass, together with those from the primary heater, to the cracking still.

By maintaining a vacuum or a sub-atmospheric pressure in the cracking zone (and preferably in the flashpot and fractionators), cracking commences at a lower temperature, while the raising of the absolute temperature, together with the turbulent and rapid motion of the vapors through the cracking tubes due to the pull of the vacuum, causes a considerable increase in the amount of heat energy taken up per square foot of surface, with a corresponding increase in the amount of cracked products. Without limiting ourselves to one specific set of pressures, we have found in actual practice that suitable pressures for our system and our method are from 0 to 60 pounds on the primary heating still, from 12 to 14 pounds absolute pressure on the flashpot, and from 6 to 14 pounds absolute (or a higher vacuum) on our cracking zone, fractionating towers, cooler and separator. It is to be understood that the word "vacuum" as used in this specification means therefore any pressure below that of the atmosphere, but the actual pressures employed will be stated in pounds absolute.

A particular feature which we shall claim herein both broadly and specifically, is the arrangement of the unit structure containing the preheating still and the cracking tubes. We preferably arrange this with twin furnaces connected by an arched overhead opening, with burners in both furnaces. The heat passing upward in the cracking furnace then follows a down draft through the preheating furnace, which has upper and lower flue passages into the stack, containing dampers by means of which the heat supplied to the preheater tubes may be regulated.

The details of construction will sufficiently

appear from the description hereinafter.

Our invention is illustrated in the accompanying drawings in which

5 Fig. 1 is a diagrammatic side elevation with parts in section showing the general arrangement of our apparatus.

Fig. 2 is a vertical transverse section of the preheater and cracking still taken on the line 2—2 of Fig. 3.

10 Fig. 3 is a horizontal longitudinal section of the same, taken on the line 3—3 of Fig. 2.

15 Referring to the drawings, and first to Fig. 1, 1 designates a flashpot adapted to receive the heated oil through valve 23 and pipe 52 from the pipe still in the furnace 2a. Charging stock is forced into said pipe still through the pipe 53 by pump 54. The oil may enter the flashpot as vapors already 20 formed, or it may be superheated oil up to the point of its entrance into the flashpot and transformed to vapor in this pot by release from or reduction of pressure. The vapors from this flashpot passing through 25 pipe 55 to the cracking tubes 56 in the furnace 2, will be at or above the equilibrium boiling point of the oils from which they are produced. This equilibrium boiling point 30 is referred to the temperature of the vapors under such pressures as that carried on our flashpot. This is a vapor temperature and not an oil temperature. The oil before entering the flashpot 1 in order to be converted completely into a vapor therein, must be 35 at a temperature somewhat above this vapor temperature in order to contain enough heat to take care of the latent heat of vaporization of the oil on entering the flashpot.

40 The preheating of the oil before it enters the flashpot is accomplished in an improved still of our design, one form of which is shown in Fig. 1 and another form in Figs. 2 and 3. In Fig. 1, the pipe still 57 is located in the furnace chamber 2a which is 45 preferably supplied with top and bottom flue openings 58—59 into the stack 60, each opening being provided with a damper as shown, so that the draft through the pipe 57 may be regulated. The furnace chamber 50 2a is provided with burners 61, which are manipulated in a manner presently to be described and the entire structure of the furnace and the pipe still is connected to the structure of the furnace 2 containing 55 the cracking tubes 56, and main burner 62. The two chambers 2 and 2a are connected in this case by means of one or more openings 63 so that the heated gases and products of combustion from the burners 62, after 60 passing through and around the cracking tubes 56, will be drawn through the passages 63 and then enter the stack 60 through either the lower or upper opening 59 or 58, according to the adjustment of the dampers 65 or equivalent devices. With the upper

70 draft of 58 open, all the waste heat from the cracking furnace 2 passes through and around the preheating tubes 57, and the oil therein is thus raised to a temperature suitable for flashing and introduction as vapors into the cracking tubes 56.

75 The burners 61 placed under the primary heating tubes are used in bringing the plant on stream at the beginning of a run. By using these burners 61 we do not have to fire the cracking tubes 56 (by means of burner 62) so heavily as would otherwise be the case and the temperature of the oil in the primary tubes is quickly raised to such a point that vapor is formed when released to the flashpot 1. After the plant is once on stream and the maximum fire is placed under the cracking tubes 2 by burners 62, the burners 61 may be turned down very low or completely cut out and the temperature of the oil flowing in the primary heater may thereafter be regulated by the proper use of the dampers as already stated. We believe this method of apparatus for preheating and cracking the oil is original with us and we shall claim the same accordingly.

80 Referring to Figs. 2 and 3, we have there- 85 in shown a modified form of preheater and cracking still in one unit structure, which we prefer to use in practice. It will be understood that the form shown in Fig. 1 is somewhat simplified as forming a part of the diagram in that figure, while Figs. 2 and 3 show an actual working structure. In 90 these figures, the enclosure 2a is built on the side of the main furnace 2, and they are connected by an arched roof 2z. The cracking tubes 56 and the preheating tubes 57 are 95 disposed horizontally and parallel to each other in the two chambers 2 and 2a, with their bends lying outside the end fire walls of the respective chambers, and enclosed with thin metal plates 65—66—67—68. The furnace 2 is lengthened out at both ends as 100 shown in 2x and 2y, these two ends being arched as indicated in dotted lines 2w in Fig. 2, and constituting dutch ovens projecting into which are the burners 62. Burners 61 project into the furnace 2a beneath the preheating tubes 57 and all the 105 burners in practice are fitted with appropriate valves. In operation the heated gases and products of combustion from the burners 62 are received in the dutch ovens 2x and 2y, and conveyed through the arches 2w into the central chamber 2, passing upwardly therein through and around the cracking tubes 56 and thence being deflected by the arch 2z through the passageway 63a into the chamber 2a. If the burners 61 are in 110 operation at the same time, for purposes of bringing the plant on stream, then the damper in the upper flue 59 should be open and that in the lower flue 58 should be closed.

After the plant is on stream as already stated, and the maximum fire is placed under the cracking tubes 56, then burners 61 may be turned down very low or completely cut out, and by regulating the dampers in flue passages 58—59, more or less of the heated gases coming through the passage-way 63a may be deflected downwardly through and around the preheating tubes 57, and into the stack 60 through the lower flue passage 58. The preheater and cracking still thus combined in one unit have certain definite advantages in point of accessibility, as well as the primary advantages of efficiency and economy.

The vapors from flashpot 1 are drawn through the cracking tubes 56 preferably at a temperature from 1000° F. to 1200° F., and as already stated a pressure of 6 to 14 pounds absolute is maintained on the cracking tubes by vacuum pump 14. This low pressure on the vapors causes the temperature at which the cracking reaction takes place to be lowered. It also causes the velocity of the vapors, considering a constant gallonage of raw oil charged, to be higher than in a system operated at or above atmospheric pressure, and this vapor velocity gives a more turbulent flow of the vapors in the tubes causing a greater heat transfer per square foot of heating surface. The vacuum pump 14 is located in such a position with suitable connections, lines 30, 39, 40, and 42, and valves 3, 4, 5, 19, 46, 20, 21 and 25, that the vacuum may be applied at the discharge from the tubes in the heating zone 2 pumping the vapors so removed from the tubes to cooling and separation tower 6, or the vacuum may be applied on the separator drum 10 and the vapors so removed discharged into absorption tower 11.

The vapors entering the cooling and separation tower 6 may be at or below atmospheric pressure, depending on the point at which the vacuum is applied to the system, and will be at an elevated temperature, preferably from 1000° F. to 1200° F., depending on the temperature found most suitable for treatment of the vapors being passed through the system to give the largest practical yield of gasoline or related light oils. Because of this elevated temperature of these vapors they contain considerable quantities of heat that must be removed before the products of the reaction produced in the tubes can be condensed and made to be stable under atmospheric conditions. This heat is removed in two ways (1) by causing the hot vapors to come in contact with a downward flow of liquid oil, drawn from the bottom of cooling and separation tower 7, by pump 13 and discharged through valve 18 to tower 6, preferably contacted with the hot vapors over a series of baffle plates placed in this tower, and (2)

by causing the vapors to come in contact with cooling coils 26, 26', 26'', and 26''' placed in this tower, through which oil of relatively lower temperature than the vapors is caused to flow by pump 15. This causes the heat to be removed by (1) vaporizing the incoming oil from tower 7, and (2) by the absorption of the heat by the cooler oil flowing in the cooling coils. This cooling effect will cause a heavy residue to collect in the bottom of the cooling and separation tower 6 which is removed from the system by pump 12, as presently described.

The vapors from cooling and separating tower 6 enter the cooling and separation tower 7, at or below atmospheric pressure depending on the point at which vacuum is placed on the system and in tower 7 they are further cooled and fractionated. This tower is preferably of the bubble type. The cooling is effected by causing the vapors to come into contact with cooling coils 27' and 27, placed in this tower, through which oil of relatively lower temperature than the vapors entering the tower is caused to flow by pump 15. The cooling in this tower is carried to such a point that a large portion of the vapors entering it are caused to condense to liquid. This liquid is drawn from tower 7 by pump 13 which discharges a part of it into tower 6 at 18 and a part through the coils 26, 26', 26'', and 26'''. Valves 18 and 47 are so located on the discharge line from pump 13 that all or any part of the liquid from the bottom of the cooling and separating tower 7 may be caused to discharge into either the tower 6 or the coils 26, 26', 26'', 26'''.

The vapors from the cooling and separation tower 7 enter another cooling and separation tower 8 at or below atmospheric pressure depending on the point at which the vacuum is applied to the system, and in tower 8 they are further cooled and fractionated. This cooling and separation tower is preferably of the bubble type. Cooling is effected by causing the vapors to come in contact with the coil 28 through which oil at a lower temperature than the vapors is caused to flow by pump 15. This cooling allows a considerable portion of the vapors to be condensed and the condensed fractions are removed from the bottom of the tower through the heat exchanger 17 by the pump 15. A part of the oil, after having been cooled by passing through the heat exchanger 17, is discharged by pump 15 through valve 31 into the absorption tower 11, and a part of the oil is discharged through coils 28 and 27, 27' through valve 32. Valves 31 and 32 may be so opened or closed as to cause a desired quantity to flow in either direction, or all or any part of the flow to go in either direction.

The vapors in the cooling and separating tower 8 are also cooled by the liquid from the bottom of the absorption tower 11 which is pumped from tower 11 by pump 16 through heat exchanger 17 where the temperature of this liquid is raised by liquid flowing in a counter current from the bottom of tower 8, and it is then discharged into tower 8 through valve 33. The temperature of the liquid entering tower 8 may be controlled by by-passing the heat exchanger with a portion of the cold liquid from absorber 11. This by-pass may be of any suitable or desired construction, and is shown at α in the drawings. The liquid from absorber 11 contains the very light fractions not condensed by water cooling coil 9. These absorbed light fractions are removed from this liquid on its entrance into tower 8 due to the heat it gains in heat exchanger 17 and the hot vapors entering tower 8.

The vapors from the cooling and separation tower 8 are caused to pass through water cooling coils 9 where they are condensed at atmospheric pressure or lower depending on the point at which the vacuum is applied to the system. This condensate, because of the cooling and separation it has previously had, is gasoline or related light oils and is collected in separator drum 10. This light liquid is removed from the separator drum 10 through valve 29 by a pump not shown in the drawings.

The vapors that collect in separating drum 10 are either drawn from it by vacuum pump 14 or are caused to pass into absorbing tower 11 by reason of their own pressure. This depends on the point at which the vacuum is being applied to the system. These vapors flow in a counter-current to the cooled liquid from the bottom of the cooling and separating tower 8 and the lighter gasoline or related lighter oils are absorbed in this liquid. The tower 11 is preferably of the bubble type.

The fixed gases pass from the tower 11 through line 47 to the atmosphere, or are conducted to burners under the furnace, or are conducted to commercial gas lines.

The bottoms from tower 8, either with or without make-up oil, delivered through line 34 and valve 35, not required as absorption oil in the tower 11, are returned to the system and used as cooling oil in coils 28, 27, 27', 26, 26'', 26''', which are placed in towers 8, 7 and 6. The line conducting this oil to cooling coils 28, 27 and 27' has valves 36 and 37 so situated that all or any part of this liquid can be caused to flow through them. The heated liquid from coils 26, 26', 26'' and 26''' is conducted through line 22 and through valve 38 to flash pot 1 where all or a considerable portion of this oil is vaporized. The vapor so produced is re-

treated in the furnace 2 by being drawn through the tubes placed in this furnace.

It is to be understood that the above apparatus is only one of the forms of apparatus that may be used to obtain light oils from hydrocarbon vapors by our process. The form of apparatus is governed largely by the nature of the vapor under treatment.

The apparatus described above when operated on vapors from petroleum gas oil of approximately 30° Bé. gravity with a vacuum capable of holding up a 5-inch column of mercury maintained on the system at the separation drum valve 29, gave a yield of 16 to 60 percent of light oils having a new Navy gasoline boiling range and 3 to 5 percent of absorbed light oils which when separated resembled natural gasoline in its boiling range. This gasoline is high in unsaturates and aromatics containing from 60 to 80 percent unsaturated compounds and from 10 to 25 percent of aromatic compounds, and is a very desirable motor fuel.

Having thus described in general the operation of our system, it may be remarked that by varying the combinations of valves, pumps, direct and reflux feed, it is possible to use the same apparatus in various ways and for different operations, with different classes of oils. The type of equipment used in our process will, of course, also vary with the kind of vapors under treatment. The equipment shown in our drawings is that used when operating on vapors produced from 28 to 36 gravity gas oil derived from petroleum. The apparatus as shown is designed to crack the vapors in the most efficient way, and then remove the heat from the cracked vapors in such a manner that the heat so removed will not be lost but taken up by oil that is to be vaporized and returned to the cracking zone. In this case the heat is removed in four successive stages, in such a manner as to cause the vapors to condense forming into four different products, one of these products being the finished gasoline or related light oil—the desired product for which the plant was designed—another product being a heavy residuum, and the two other products being a heavy and light gas oil respectively which are used in the system to maintain the desired temperature on the incoming vapors, and as an absorbing oil to remove the very light gasoline like material that is entrained in the gas from the separator drum.

In operation, the first tower 6 is used largely as a heat exchanger between the incoming vapors from the cracking tubes in the furnace 2 and the oil being charged into the system, from which vapors are to be produced. The vapors which enter this tower are at a relatively high temperature, that temperature being from 1000° F. to 1200° F. In this tower the surface of the

coils 26, 26', 26'', 26''' containing the charging oil should be such as to transfer enough of the heat contained in the vapors to the charging oil so that the vapors leaving this tower will be at from 720° to 650° F. At this temperature there will be a very heavy asphaltic material removed from these vapors which if allowed to remain in the tower 6 would eventually harden and plug the tower due to the heat of the incoming vapors. To keep this from happening we provide valve 18 through which a quantity of the heavy gas oil from the bottom of #7 tower may be introduced into tower 6. This heavy gas oil dissolves the asphaltic material removed from the vapors in tower 6 and carries it to the bottom of the tower where it is drawn off by pump 12 as a liquid residue suitable for fuel oil. The heavy gas oil introduced into this tower also serves as an added cooling medium for the incoming vapors and gives us a more flexible control over the temperature of the gases leaving the tower. This tower 6 contains at its top the heat exchanger shown in the drawings as coils 26, 26', 26'' and 26''' and in the bottom it contains baffle pans over which the heavy gas oil being introduced into the tower is made to flow to keep it washed free of the heavy asphalt-like material. Of course it is not necessary that this tower contain baffle pans only as shown, for anything placed in the tower which will contact the gases with the heavy gas oil and at the same time cause it to flow around in the tower to dissolve all asphalt-like material will do equally as well, as an equivalent of the baffle pans.

The temperature of the vapors entering tower 7 should be approximately at the equilibrium boiling point of these vapors under the conditions maintained in that tower. At this temperature the quantity of heat to be removed from these vapors is only that heat due to the condensation of the heavy gas oil we desire to remove in tower 7 and the heat we must extract from the vapors themselves in order to cool the vapors to such a temperature that the heavy gas oil will liquefy and drop out of the vapors. The heat to be removed in this tower is not so great in quantity as that removed in tower 6, therefore the heat exchanger at the top of this tower, which has a surface only sufficient to transfer the heat from the vapors to the liquid flowing in this exchanger, is smaller than the heat exchanger in tower 6. We have indicated this reduction in size in the drawings by placing only two coils 27 and 27' in this tower. In cooling the vapors in this exchanger under the conditions mentioned there is a certain quantity of lighter oils which will be absorbed from the vapors by the condensing heavy gas oil. In order to thoroughly strip this heavy gas oil of these light oils we cause these condensed heavy gas oils to flow downward through the tower over a series of bubble pans 50 in contact with the vapors entering this tower. Of course it is not necessary that these be bubble pans specifically, but may be any thing that will give the condensate proper contact with the incoming vapors so that the absorbed light oils will be removed from the heavy gas oil before it is withdrawn from the tower by pump 13. Even an open column below this condenser would suffice if made long enough. However, we have chosen to use and illustrate bubble pans because we can thereby cut down the length of the tower and also cut down the heat of radiation, thereby lessening the heat losses of the system.

Tower 8 operates on the same general principles as does tower 7, except for the fact that it is used to remove the light gasoline absorbed from vapors entering tower 11. In this tower enough heat is taken from the vapors entering it to cause the condensation of a light gas oil and to cool the vapors to where they are made up of only fixed gases and the desired gasoline like vapors. As the quantity of heat removed in this tower is less than the heat to be removed in the preceding towers, we have shown the heat exchanger at the top of this tower with only one coil, 28. Below this coil we have bubble pans 51 which serve to strip the condensed light gas oil of its absorbed gasoline and also to strip the absorbing oil from tower 11 of its light gasoline line by contacting them preferably in counter-current with the incoming vapors. As in the other tower we could get the same effect without bubble pans but they are given preference here for reasons already stated.

The vapors from tower 8 pass to water cooler 9 where they are brought to atmospheric temperature under which condition the gasoline like material is all condensed except for that entrained in the fixed gases. This condensed liquid and fixed gases are separated in drum 10, the gasoline like material going to storage or any other place desired and the fixed gases passing to tower 11 where they are stripped of their entrained light gasoline by flowing counter current to a down flow of light gas oil removed from the bottom of tower 8 or other light gas oil introduced from an outside source through valve 35.

The light gas oil from the bottom of tower 8 is drawn through heat exchanger 17 by pump 15 where it loses its heat to cold oil drawn from the bottom of tower 11. This exchange of heat here cools the light gas oil from tower 8 to such an extent that it can be used in tower 11 to such a degree that when it is introduced again into tower

8 very little added heat from vapors entering tower 8 is necessary for the complete removal of the light gasoline this oil has absorbed while passing through tower 11. By 5 this system of stripping the absorbing oil of its light gasoline content in the presence of the heavier gasoline vapors, we get a product more stable under atmospheric conditions than is gasoline produced in the 10 ordinary way and having the light stripings from the absorbing oil added to it afterwards. In other words, the absorbing tower 11 operating in connection with the tower 8, constitutes a stabilizing system 15 which also takes advantage of the heat available in bottoms from tower 8, and uses the same to strip the absorbing oil of its light gasoline content.

What we claim is:

- 20 1. Apparatus for the treatment of hydro-carbon oils comprising in combination an initial heater adapted to retain pressure, an expansion chamber or flashpot, means for releasing initially heated oils from said heater into said expansion chamber or flashpot, a still having an open connection to said flashpot adapted to receive the oils therefrom and means to heat the oils in the vapor phase in said still to cracking temperature, cooling and separating means connected to receive the cracked vapors, and suction means connected so as to create and maintain a constant vacuum or subatmospheric pressure on the oil vapors in said cracking still and through its open connection with the flashpot on the content of said flashpot, together with means to receive condensed oils from the cooling and separating means, and means to pass the same back under pressure to the flashpot for retreatment, 35 without passing through the initial heater.
2. Apparatus for the treatment of hydro-carbon oils comprising in combination an initial heater adapted to retain pressure, an expansion chamber or flashpot, means for releasing initially heated oils from said heater into said expansion chamber or flashpot, a still having an open connection to said flashpot adapted to receive the oils therefrom and means to heat the oils in the vapor phase in said still to cracking temperature, cooling and separating means connected to receive the cracked vapors, and suction means connected so as to create and 40 maintain a constant vacuum or subatmospheric pressure on the oil vapors in said cracking still and through its open connection with the flashpot on the content of said flashpot, together with means to receive condensed oils from said cooling and separating means, means to reheat the same to a suitable temperature for flashing into vapors again, and means to pass the same when re-heated under pressure back into the flashpot.

3. Apparatus of the class described, comprising means for initially heating oil to a vaporizing temperature while maintaining pressure thereon, a flashpot and means to release the oil therein, a cracking still connected to said flashpot and adapted to receive the oil therefrom and means to maintain a sub-atmospheric pressure thereon, means to heat the same therein to cracking temperatures, fractionating means connected to receive cracked vapors from the cracking still and to separate and condense heavier fractions thereof, and power driven pumping means suitably connected to receive and force condensate under pressure into and through said fractionating means in a counter direction to the incoming cracked vapors, whereby heat from said vapors is transferred to said condensate, means to conduct said condensate thus reheated to the flashpot, and means to release the same therein.

4. Apparatus of the class described comprising a primary heater, a flashpot, a cracking still or retort, fractionating means, a cooler and separator, and oil and vacuum pumps, said fractionating means comprising a plurality of units connected in tandem, the last element being connected also in tandem with the cooler and the separator, said vacuum pump being connected to produce a sub-atmospheric pressure on the entire system from the cooler back to said cracking retort, and said oil pump being adapted to remove the condensate from the last fractionating unit and to force the same back under pressure to the flashpot, with a heat exchanger consisting of a closed system of piping extending through tandem coils in the several fractionating units, from said oil pump to said flashpot.

5. Apparatus as described in claim 4, comprising the additional element of an absorption tower, a cooler and separator adapted to condense and separate all gasoline-like material passing over from the last fractionating unit, except that entrained in the fixed gases, means to convey said fixed gases with entrained gasoline into said absorption tower, and means to produce a counter current through said tower of condensate and make-up oil to absorb said gasoline, a pump acting to deliver said oil and the absorbed gasoline to a fractionating unit preceding the cooler and separator, wherein the same absorbs heat and the gasoline is thereby removed from said oil, passes over to the cooler, and is cooled and condensed.

6. Apparatus for the treatment of hydro-carbon oils comprising in combination an initial heater adapted to retain pressure, an expansion chamber or flashpot, means for releasing initially heated oils from said heater into said flashpot, a still having an open connection to said flashpot adapted to receive the oils therefrom, and means to heat

the oils in the vapor phase in said still to cracking temperature, cooling and separating means connected to receive the cracked vapors, said preheating still, expansion chamber or flashpot, the cracking still, fractionating means and condensing means, all connected in tandem, a vacuum pump, and a suction pipe leading therefrom with valved connections to the output terminal of each of a plurality of said elements whereby a sub-atmospheric pressure may be maintained on any unit or group of units or on the entire system, according to the nature of the crude material being treated, and the product desired.

7. Apparatus for the treatment of petroleum oil comprising a preheater, means for heating and means for maintaining pressure in said heater, a flashpot with its input connected to the output of said heater, a cracking still connected to the output of said flashpot, a plurality of fractionators or dephlegmators connected in tandem with their first input connected to the output of said cracking still, a cooler and separator connected to the last output of said fractionators, a suction pump and a valved suction pipe extending therefrom adapted to produce forward suction through the system and a subatmospheric pressure on said cracking still and flashpot, an oil pump with a feed pipe connected therefrom to the output of the last fractionator, and a pressure pipe extending therefrom through heating coils in the several fractionators to the flashpot, whereby suction is exerted forward through the system and pressure is maintained backward through the system on the distillate or make-up oil as it is heated until it is released into the flashpot.

In testimony whereof we hereunto affix our signatures.
